UNITED STATES PATENT OFFICE.

EDWARD D. PRIEST, OF SCHENECTADY, NEW YORK, ASSIGNOR TO THE
GENERAL ELECTRIC COMPANY, OF NEW YORK.

DESIGN FOR A CORE-PLATE FOR DYNAMO-ELECTRIC MACHINES.

SPECIFICATION forming part of Design No. 30,102, dated January 31, 1899.

Application filed November 4, 1898. Serial No. 695,511. Term of patent 14 years.

To all whom it may concern:

Be it known that I, EDWARD D. PRIEST, a citizen of the United States, residing at Schenectady, county of Schenectady, State of New York, have invented a new and original Design for Core-Plates for Dynamo-Electric Machines, (Case No. 990,) of which the following is a specification.

The accompanying drawing shows a core-plate shaped in accordance with my invention.

The leading feature of the design is the core-plate having teeth of the configuration substantially as shown in the drawing.

Referring to the drawing by letter, A represents the main body of the core-plate, and extending therefrom are a number of teeth B, and between the teeth are formed coil-slots C for the reception of the armature-coils. The teeth are highest at B', which is the central portion of the tooth, and from this point the height of the tooth gradually decreases toward the coil-slots on each side of the tooth. This decrease in height may be obtained by

curving the end of the teeth, as shown in the drawing. By constructing the teeth so that they are highest in the center and gradually decreasing in height toward the coil-slots the teeth will enter and leave the field of each pole-piece in a more smooth and gradual manner. A second advantage in constructing the teeth as shown lies in the fact that the armature-coils can more readily be slipped into place. The central or body portion of the core-plate is provided with a hole D to receive a shaft, and also a keyway E.

What I claim as new, and desire to secure by Letters Patent of the United States, is—

The design for a core-plate for a dynamo-electric machine, substantially as shown and described.

In testimony whereof I have hereunto set my hand this 1st day of November, 1898.

EDWARD D. PRIEST.
